UNITED STATES PATENT OFFICE.

CHRISTIAN C. SCHWANER, OF WINTerset, IOWA.

HAME-TUG.

SPECIFICATION forming part of Letters Patent No. 286,250, dated October 9, 1883.

Application filed April 17, 1883. (No model.)

To all whom it may concern:

Be it known that I, CHRISTIAN C. SCHWANER, of Winterset, in the county of Madison and State of Iowa, have invented an Improved 5 Harness Hame-Tug, of which the following is a specification.

The object of my invention is to diminish the cost and increase the efficiency and durability of a hame-tug, and also to thereby improve 10 the artistic appearance of a complete harness.

It consists, first, in forming a metal strap or base-piece adapted to be covered by nailing or tacking leather thereto by means of common 15 tacks, and combining a metal clamping-plate, metal loops, a hame-tug clip, and one piece of a two-part trace-buckle therewith by means of hinge-sections formed integral with the metal base and the metal cover or clamping-plate; 20 second, in the manner of forming a metal hame-tug section and loop integral with each other to produce a flexible joint and adjustable loop in the complete hame-tug at a point that will allow the tug to bend and adjust itself relative 25 to the shoulder of a horse and the collar on the horse, all as hereinafter fully set forth.

Figure 1 of my accompanying drawings is a perspective view of my improved hame-tug. Fig. 2 is a longitudinal section of Fig. 1. Fig. 30 3 is a top view of my metal base-piece. Fig. 4 is a longitudinal section of one of the ends, and Fig. 5 a transverse section of Fig. 3. Fig. 6 shows the metal top plate or clamping-cover in an inverted position. Fig. 7 is a longitudinal section, and Fig. 8 a transverse section, of 35 Fig. 6. Fig. 9 is a top view, showing part of a buckle hinged to the rear end of my tug, and a cockeye-clip to the front end, to produce a short tug, in such a manner that they can be 40 readily detached and replaced at pleasure. Fig. 10 is a transverse section near a loop, and looking toward the loop. Fig. 11 is a longitudinal section, showing the fins on the pivotal bar of a loop. Fig. 12 is a transverse section, 45 showing one of the fins on the loop. Jointly considered, these figures clearly illustrate the construction, and operation, and utility of my complete invention.

a is the flat body of my metal base-plate. 50 It has flanges *a'* at its sides, at the top edges, to strengthen it and to form a panel

within which to lay a corresponding strip of leather.

a'' are open hinge-sections formed integral with the ends of the metal strap *a* in such a 55 manner that the cross-bar of a metal loop, buckle, or cockeye-clip can be readily inserted, and secured thereto by means of the overlapping ends of the clamping-plate.

a''' are screw-seats formed integral with the 60 ends of the same strap and base, *a*.

b is a metal plate corresponding in length with the part *a*. It is preferably oval on its top surface and ribbed on its flat under side. It has transverse bearings *b'*, adapted to admit 65 the cross-bars of metal loops, and to facilitate pivoting and securing loops to the complete tug; or loops may be cast solid therewith.

b'' are hinge-sections formed integral with the ends of the plate *b*, and adapted in form to 70 overlap the cross-bar of a loop, buckle, or cockeye-clip placed in the hinge-section *a''* of the base-piece *a*.

b''' are screw-holes in the plate *b*, coinciding with the fixed nuts or screw-seats *a'''* in the 75 base-plate *a*.

c are the ends, *c'* the top cross-bar and loop, and *c''* the parallel cross-bars, of my hame-tug section, cast complete in one piece for the purpose of making a flexible joint in a long 80 hame-tug.

d is the cross-bar of my improved metal loop, having fins *d'* formed integral with its sides to restrict the rocking motion of the bar and complete loop, and to hold the loop at right 85 angles relative to the tug.

To construct a complete tug without stitching, I first inlay a piece of leather, *f*, upon the flanged top surface of the metal strap and base *a*, and then bend the edges of a piece of leather, *g*, around and over the base, to overlap the leather *f*, and to fasten them together by simply driving common tacks through the parallel and meeting edges of the cover *g* and down through the leather *f*, to be clinched upon the 90 top surface of the metal base *a*, as clearly shown in Figs. 10, 11, and 12. To cushion the edges of the metal base, I simply wrap a strip of cloth or other suitable flexible material upon the metal, as indicated in Fig. 3, before covering it with leather. I next place my hame-tug section and loop, or a cockeye hame-clip, 95

in the front end of the hinge-section a'' of the leather-covered base-piece a , and a trace-buckle, or part of a trace-buckle, in the hinge-section at the rear end, and secure them by 5 simply placing the metal covering and clamping plate b (after it is extended through metal or leather loops) upon the leather-covered base, and then inserting screws Nos. 1 and 2 into the coinciding openings or screw-seats a'' 10 and b'' , to clamp and fasten the parts together and to finish the tug.

I claim as my invention—

1. A metal strap and base-piece for a hame-tug, having hinged section at each end, and per- 15 forations or screw-seats, and flanged panels adapting it to have a leather covering, a metal hame-clip, loops, and a buckle detachably connected therewith by means of a clamping-plate, to produce a complete hame-tug with- 20 out stitching.

2. The combination of the metal tug-strap a , having hinge-sections a'' and nuts or screw-seats a''' , the metal tug-section and loop $c c' c''$, one or more loops, a trace-buckle or part of a 25 buckle, and a metal clamping-plate, $b b' b''$,

substantially as shown and described, to produce a long and jointed hame-tug.

3. The combination of the metal tug-strap a $a'' a'''$, having a leather covering, a cockeye hame-clip, one or more loops, and a metal 30 clamping-plate, $b b' b'''$, substantially as set forth, to produce a short hame-tug.

4. A metal hame-tug section and loop composed of the ends c , top bar, c' , and two parallel bars, c'' , in combination with the hame-tug, for the purpose specified. 35

5. An improved hame-tug, composed of a metal strap and base having hinge-sections and perforations or screw-seats at its ends, a leather covering, a metal clamping-plate having hinge-sections and perforations coinciding with the hinge-sections and perforations or screw-seats in said strap and base, a detachable hame-clip, a detachable buckle or part of a trace-buckle, and one or more detachable loops, in 40 45 the manner set forth.

CHRISTIAN C. SCHWANER.
